ENGINE STARTER

John W. Fitz Gerald, Milwaukee, Wis., assignor to
 Briggs & Stratton Corporation, Milwaukee,
 Wis., a corporation of Delaware

Application April 10, 1942, Serial No. 438,462

9 Claims. (Cl. 74—7)

This invention relates to engine starters of the type wherein the drive pinion is automatically propelled to and from mesh with the engine ring gear.

In general it has been found that the ideal construction for starters of this type comprises a driving head adapted to be secured to the shaft of the starter motor, an actuating member loosely mounted on the motor shaft or a sleeve slipped thereon and carried by the driving head, and a tubular extension on the pinion threaded onto the actuating member.

By virtue of the threaded connection between the actuating member and the pinion sleeve or extension, relative rotation between these parts effects longitudinal motion of one with respect to the other, depending upon the direction of relative rotation. Hence, by transmitting torque from the drive head to the actuating member the desired translation of the pinion along the shaft is accomplished, such movement of the pinion being limited by a suitable stop upon attainment of full meshing relationship.

The parts thus far described and operating in the manner stated, accomplish the desired translation of the pinion along the shaft to and from mesh with the ring gear, but yieldability must be incorporated to cushion the application of the engine load on the starter motor and also to accommodate occasional collision of the teeth on the starter pinion with those of the ring gear.

The means by which this necessary yieldability has been incorporated in starters in the past has taken many different forms.

In some instances the yieldable means has been interpositioned between the pinion and the actuating member, but most generally and practically, it constituted the driving connection between the actuating member and the drive head which is fixed to the motor shaft.

In the early type starters yieldability was obtained through the use of a coiled spring which combined torsional and endwise resiliency. Inasmuch as the torque had to be transmitted through the spring its crystallization and the consequent failure of the starter was a common occurrence. A vast improvement over the early type starter was obtained through substitution of a rubber collar as the yieldable driving connection between the actuating member and the drive head, as evidenced by Patent No. Re. 20,686, dated April 5, 1938.

The use of rubber as the yieldable driving connection not only eliminated the objection of fail-

ure due to crystallization of the spring, but it produced a much quieter starter.

However, with the increasing difficulty of obtaining rubber, either natural or synthetic, further revision of starters of this type must be made, and it is therefore an object of this invention to provide an engine starter which retains all the desirable constructional characteristics of past starters but utilizes an entirely new manner of obtaining the necessary yieldability which, though it incorporates the use of a spring and eliminates the need for rubber, is free from the objections inherent in the earlier use of springs.

15 In general this invention achieves this result through the use of a yieldable driving connection between the actuating member and the drive head formed conjointly by a compression spring which carries none of the driving torque and a novel torque transmitting cam connection arranged to reduce the load on the spring.

20 Another object of this invention resides in the provision of a novel yieldable driving connection for starters of the character described which is so designed that any desired gradient of resistance to endwise thrust imparted to the actuating member may be built into the starter.

25 Still another object of this invention is to provide means for insuring quietness in operation by 30 yieldingly maintaining the cam surfaces on the actuating member and drive head engaged at all times.

With the above and other objects in view, which will appear as the description proceeds, 35 this invention resides in the novel construction, combination and arrangement of parts substantially as hereinafter described and more particularly defined by the appended claims, it being understood that such changes in the precise 40 embodiment of the herein disclosed invention may be made as come within the scope of the claims.

The accompanying drawings illustrate several 45 complete examples of the physical embodiment of the invention constructed according to the best modes so far devised for the practical application of the principles thereof, and in which:

Figure 1 is a side view of a starter embodying this invention, with parts thereof broken away and in section and showing the pinion in 50 its retracted inactive position;

Figure 2 is a view similar to Figure 1 but showing the pinion advanced into mesh with the ring gear;

Figure 3 is a perspective view of the drive head 55 unit;

Figure 4 is a perspective view of the compression spring and the actuating member which are assembled on the sleeve of the drive head unit;

Figure 5 is a cross sectional view taken on the plane of the line 5-5 in Figure 1;

Figure 6 is a side view of part of the starter and illustrating the manner in which the cam parts may be yieldingly held in engagement;

Figure 7 is a view similar to Figure 6 illustrating the manner in which the load proportionately carried by the spring and the cam may be balanced between them to obtain any desired gradient of resistance to end thrust;

Figure 8 is a perspective view of the drive head unit of the starter construction shown in Figure 7; and

Figure 9 is a perspective view of the actuating member construction employed in the starter shown in Figure 7.

Referring now more particularly to the accompanying drawings, in which like numerals indicate like parts, the numeral 5 designates the ring gear of an engine to be started and with which the pinion 6 of the starter meshes during the starting cycle.

The pinion 6 has a rearwardly extending sleeve or tubular extension 7 internally threaded to fit the threads 8 of an actuating member 9. The actuating member comprises a flange 10 having a forwardly directed tubular extension 11 on which the threads 8 are formed and a rearwardly directed cylindrical projection 12. This rearwardly directed cylindrical projection 12 is stepped to provide diametrically opposite narrow and wide portions 13 and 14.

One end of the wide portion 14 terminates in an abrupt step 15 parallel with the axis of the actuator, but at its opposite end an inclined cam surface 16 constitutes the step between the two portions 13 and 14. This inclined cam surface 16 cooperates with a correspondingly inclined cam surface 17 on a drive head indicated generally by the numeral 18.

The drive head 18 comprises a sleeve 19 telescoped over the shaft 20 of the starter motor and a boss 21 fixed to the sleeve. A suitable key and screw connection locks the drive head to the motor shaft.

Carried by the boss 21 and projecting radially therefrom is an annular flange 22. This flange 22 is of the same diameter as the cylindrical extension 12 on the actuating member and projecting forwardly therefrom is a cylindrical extension 23 complementary in shape to the extension 12, that is, it is stepped and has narrow and wide portions 24 and 25, respectively.

One junction between these portions is formed by the inclined cam surface 17 and its opposite junction is in the form of a square shoulder or step 26. This shoulder 26, however, is angularly or circumferentially displaced from the shoulder 15 when the actuating member is assembled with the drive head and the cam surfaces 16 and 17 are in engagement, as shown in Figure 5.

This clearance is provided to insure unhindered functioning of the cam connection.

Interposed between the flanges of the actuating member and drive head is a compression spring 27 which yieldingly holds the actuating member longitudinally away from the drive head, and to limit the movement apart of these elements under influence of the spring, a retaining shell 28 is applied over the flanges of the actuating member and drive head. This shell has an inwardly directed flange 29 engaging behind the

flange of the drive head and has a bead 30 rolled over the edge of the flange 10 on the actuating member.

Thus, it will be seen that rearward longitudinal displacement of the actuating member produced by the action of the screw and resulting either from collision of the pinion teeth with the teeth of the ring gear or the picking up of the engine load when the pinion is in its forward limit of movement defined by a stop 31 on the front end of the sleeve 19 is resisted jointly by the compression spring 27 and the force of friction resulting from the cam connection.

In this manner it is possible to utilize a compression spring to take the end thrust and substantially duplicate the resiliency of a rubber collar. Tests having shown that it is impossible to obtain a spring capable of installation in the space available which of itself could duplicate the action of a rubber collar as employed in starters of the type described in the aforesaid Fitz Gerald patent; but with the cam connection frictionally resisting end thrust the load on the spring is materially lessened. It is thus feasible to use a relatively light coil spring, especially as none of the driving torque is carried by the spring. The entire torque is transmitted by the cam connection.

This construction achieves all of the required yieldability in a starter as the torsional resiliency necessary to cushion the application of the engine load to the starter motor is obtained through the translation by the screw of torque load into rearward endwise displacement of the actuating member, which, of course, is cushioned.

When the engine starts the actuating member is apt to be rotated with respect to the drive head to disengage the cam surfaces and engage the abrupt shoulders 15 and 26. While this action would in nowise affect the operation of the starter, it would result in an objectionable clicking sound and might increase wear on the cam surfaces due to the hammerblow resulting from taking up the lost motion when the starter again functioned.

Hence, it is desirable to incorporate means for holding the cam surfaces yieldably in engagement. This is conveniently accomplished by means of the spring 27 merely by forming projections 32 on the ends of the spring and engaging the same in appropriate recesses in the drive head and actuating member as clearly shown in Figure 6.

With the construction shown in Figures 1 to 6, inclusive, the cam surfaces are arranged at the same angle (30° in this instance) throughout their entire length, but by changing the shape of the cam surfaces it is possible to obtain any desired progression of resistance to end thrust on the actuating member, and in Figures 7 to 9, inclusive, one manner of effecting this result is illustrated.

As here shown, the cam surface 17 on the drive head is formed as a curve and the cam surface 16' of the actuating member is merely a rounded projection arranged to ride on the curved surface 17'. Inasmuch as the curve 17' falls away from the high point of the cam with a decreasing increment, it follows that the resistance to rearward displacement of the actuating member is initially light, being carried primarily by the spring, but increases as the load on the starter builds up.

Obviously, any desired shape of cam may be employed to produce any desired action.

From the foregoing description, taken in connection with the accompanying drawings, it will be readily apparent to those skilled in the art that this invention provides a starter which retains the desirable attributes of starters using rubber as the means for providing the necessary yieldability but without necessitating such use and without incurring the objections inherent in previous uses of springs.

What I claim as my invention is:

1. In an engine starter of the type wherein a pinion is automatically propelled forwardly into mesh with an engine ring gear by rotation of an actuator from a power shaft, and wherein interference with forward propulsion of the pinion and picking up the load of the engine by the starter imparts rearward end thrust on the actuator: a driving connection between the actuator and the power shaft comprising opposed abutments on the actuator and the power shaft, said abutments being relatively movable rotarily and axially with respect to each other; yieldable means interposed between said abutments to yieldingly resist motion of the same toward each other under the influence of rearward end thrust on the actuator; and a torque transmitting connection between said abutments comprising a cam connection operable to simultaneously transmit torque and yieldingly frictionally resists relative endwise movement of said abutments toward each other brought about by rearward end thrust on the actuator to thereby aid the yieldable means in resisting such rearward end thrust.

2. An engine starter of the type wherein a pinion member is automatically propelled forwardly into mesh with the ring gear of an engine to be started by means of an actuator driven from a power shaft and having a threaded connection with the pinion member, and wherein rearward end thrust is imposed upon the actuator upon operation of the starter both prior to and during meshing of the pinion member with the ring gear, said starter being characterized by: the provision of a longitudinally yieldable driving connection between the actuator and the power shaft formed conjointly by cam means arranged to transmit torque from the power shaft to the actuator and at the same time yieldingly frictionally resist endwise movement of the actuator under the influence of rearward end thrust thereon, and a compression spring also yieldingly resisting endwise movement of the actuator brought about by rearward end thrust on the actuator.

3. In an engine starter of the type wherein a pinion member is automatically propelled into and out of mesh with an engine ring gear by means of an actuating member connected with the pinion member in a manner to effect forward propulsion of the pinion member into mesh with the ring gear during rotation of a power shaft, and wherein operation of the starter imposes rearward end thrust on the actuating member; an endwise resilient driving connection between the power shaft and the actuating member formed conjointly by a compression spring confined between opposed abutments on the power shaft and actuating member so as to yieldingly oppose rearward end thrust on the actuating member, and engaging cam surfaces on the power shaft and actuating member arranged to transmit torque and also to yieldingly resist relative movement of the abutments toward each other

under the influence of rearward end thrust on the actuating member.

4. In an engine starter having a power shaft and a pinion member movable longitudinally along and rotatably with the power shaft, said engine starter including an actuator driven from the power shaft and connected with the pinion member to automatically propel the pinion forwardly into operative relation with the engine during starting of the engine and to automatically retract the pinion upon starting of the engine: a part fixed on the power shaft; a part on the actuator in juxtaposition to said part on the power shaft; radial abutments on said parts engaging to transmit torque from the power shaft to the actuator, at least one of said abutments having a spiral cam formation so that the engagement of the said abutments frictionally opposes endwise movement thereof toward each other with a force depending upon the shape of said spiral cam formation; yieldable means interposed between said parts on the power shaft and actuator yieldingly resisting endwise movement of said parts toward each other so that said yieldable means in conjunction with said spiral cam connection yieldingly opposes endwise retraction of the actuator; and means for limiting endwise movement of said parts away from each other.
5. In an engine starter of the type wherein a pinion member is automatically propelled along a power shaft by means of an actuating member connected with the pinion member in a manner to effect propulsion of the pinion member to and from mesh with the ring gear: cooperating abutments on the actuating member and the power shaft engaging to transmit torque from the shaft to the actuating member, at least one of said abutments having its surface which engages the other abutment spirally arranged about the axis of the shaft so that while engagement of said abutments transmits torque it also yieldingly frictionally resists endwise movement of the actuating member toward the abutment on the shaft; and a spring yieldingly urging the actuating member in an endwise direction away from the abutment on the shaft, so that said spring coacts with the frictional resistance to said endwise movement of the actuating member to provide endwise resiliency in the torque transmitting connection between the shaft and actuating member.
6. In an engine starter of the type wherein a pinion member is automatically propelled along a power shaft by means of an actuating member connected with the pinion member in a manner to effect propulsion of the pinion member to and from mesh with the ring gear: cooperating abutments on the actuating member and the power shaft engaging to transmit torque from the shaft to the actuating member, at least one of said abutments having its surface which engages the other abutment spirally arranged about the axis of the shaft so that while engagement of said abutments transmits torque it also yieldingly frictionally resists endwise movement of the actuating member toward the abutment on the shaft; and a spring yieldingly urging the actuating member in an endwise direction away from the abutment on the shaft, so that said spring coacts with the frictional resistance to said endwise movement of the actuating member to provide endwise resiliency in the torque transmitting connection between the shaft and actuating member, and the spiral of said abutment decreasing in pitch so that the frictional resistance to end thrust on the actuator is progressively greater as

the endwise displacement of the actuator progresses.

7. In an engine starter of the type wherein a pinion is automatically propelled into and out of mesh with an engine ring gear: an endwise yieldable driving connection through which the transmission of torque to the pinion is effected, said connection comprising axially spaced driving and driven abutments, said driven abutment being movable toward the driving abutment during operation of the starter as a result of end thrust thereon; a compression spring between said abutments yieldingly opposing relative motion of the same toward each other; and cooperating engaging cam parts on the abutments arranged to simultaneously transmit torque and frictionally yield axially so that the end thrust imparted to the connection is carried jointly by the spring and the engaging cam parts.

8. In an engine starter of the type wherein a pinion is automatically propelled into and out of mesh with an engine ring gear: an endwise yieldable driving connection through which the transmission of torque to the pinion is effected, said connection comprising axially spaced driving and driven abutments, said driven abutment having end thrust imparted thereto during operation of the starter in a direction tending to move the

driven abutment toward the driving abutment; a compression spring between said abutments yieldingly opposing movement of the driven abutment toward the driving abutment; cooperating cam parts on the abutments engaging so as to simultaneously transmit torque and frictionally yield axially whereby end thrust imparted to the connection is carried jointly by the spring and the engaging cam parts; and means for limiting endwise movement of said abutments away from each other.

9. In an engine starter of the character described: substantially coaxial rotatable driving and driven members, the driven member being movable axially toward the driving member as a result of end thrust imposed on the driven member during the transmission of driving torque between said members; and an endwise yieldable driving connection between said members comprising cooperating cam parts thereon engaging to simultaneously transmit torque between the members and to frictionally yield axially under the imposition of end thrust on the driven member, and a spring urging said members apart and cooperating with the cam parts to aid in absorbing end thrust on the driven member.

JOHN W. FITZ GERALD.
